CLAIM

The ornamental design for a lamp for ukulele, as shown and described.

DESCRIPTION

FIG. 1 is a front elevational view of a lamp for ukulele, showing our new design;

FIG. 2 is a rear elevational view thereof;

FIG. 3 is a left side elevational thereof;

FIG. 4 is a right side elevational view thereof;

FIG. 5 is a top plan view thereof;

FIG. 6 is a bottom plan view thereof; and,

FIG. 7 is a front perspective view thereof.

The broken lines in the figures illustrate portions of the lamp for ukulele that form no part of the claimed design.
